(57) CLAIM

The ornamental design for a handheld fabric sweeper having a rounded top, as shown and described.

DESCRIPTION

FIG. 1 is an elevation view of a side of the handheld fabric sweeper having a rounded top embodying the new design; FIG. 2 is a perspective view thereof;

FIG. 3 is a perspective view from an opposite end thereof; FIG. 4 is an elevation view of one end of the handheld fabric sweeper having a rounded top;

FIG. 5 is an elevation view of an opposite end thereof; and, FIG. 6 is a top plan view thereof.

The broken line showing on the drawing disclosure is for illustrative purposes only and forms no part of the claimed design. The dash dot lines which define the bounds of the claimed design form no part thereof.

1 Claim, 6 Drawing Sheets
